[57] **ABSTRACT**

This disclosure describes a method of preventing thrombosis in mammals and inhibiting platelet aggregation which consists of administering an effective amount of a compound of the formula:

wherein X, Y and Z are as defined in the specification.

6 Claims, No Drawings

METHOD OF PREVENTING THROMBOSIS

This invention relates to a novel method of preventing thrombosis in mammals and to a method of preventing platelet aggregation. More specifically, this invention relates to a method of preventing thrombosis and platelet aggregation in mammals which consists of administering to mammals an effective amount of a compound of the formula:

wherein

X is hydrogen or hydroxy; Y is hydrogen, hydroxy, halogen, alkyl of one to four carbon atoms, alkoxy of one to four carbon atoms, or trifluoromethyl; and Z is alkylene of three to five carbon atoms, alkylene of three to five carbon atoms substituted by alkyl or alkoxy of one to four carbon atoms, divinylene, divinylene substituted by alkyl of one to four carbon atoms,

This invention also relates to a method of inhibiting platelet aggregation in blood plasma which consists of adding an effective amount of a compound of the above formula to the plasma.

The compounds utilized in these methods of preventing thrombosis and platelet aggregation and their preparation are disclosed in co-pending application U.S. Ser. No. 336,919 filed Mar. 1, 1973.

The prevention of thrombosis in mammals by the administration of the compounds of this invention is demonstrated by their ability to inhibit platelet aggregation in mammals [F. Michal and B. G. Firkin, Ann. Rev. Pharmacol. 9, 95 (1969)]. Groups of five female Lewis rats, weighing 150-175 g. each, are injected subcutaneously into plantar surface (sole) of the left hind paw with 0.1 ml *Mycobacterium butyricum* in white paraffin oil at a concentration of 5 mg/ml. On the tenth day following injection, test compounds are administered orally as aqueous suspensions (10 ml/kg) at a dose of

50 mg/kg. Control rats, five injected and five non-injected, are treated in a similar manner, but are given a vehicle solution (10 ml distilled water plus one drop of "Tween 80"). Three hours after compound or vehicle administration, the rats are anesthetized with sodium pentobarbital (50 mg/kg intraperitoneally) and blood samples are obtained from the abdominal aorta and mixed with 3.8% sodium citrate to a final concentration of 0.38%. The samples are centrifuged for 10 minutes at 200 g at 4°C. The platelet-rich plasma (PRP) so obtained is removed by a siliconized Pasteur pipette and placed on ice in a plastic tube. The remaining sample is further centrifuged at 1,300 g at 4°C for 35 minutes. The platelet-poor plasma (PPP) so obtained is removed by a siliconized pipette and placed on ice in a plastic tube. Platelet counts are performed using a Model ZBI Coulter Counter (Coulter Electronics, Inc., Hialeah, Fla.) and the final platelet count in the PRP is adjusted to 500,000/mm³ by dilution with PPP at room temperature. Platelet aggregation studies are performed using a Payton Dual Channel Aggregation Module and Recorder (Payton Associates, Inc., Buffalo, N.Y.) with disposable siliconized 0.312 cuvettes and stir bars. 0.45 ml diluted PRP is placed in a cuvette. The instrument is allowed to equilibrate at 37°C with a stirring speed of 1,100 rpm and is calibrated with the corresponding PPP. After establishing the baseline, 0.05 ml Plain Tyrodes Buffer pH 7.35 is added and aggregation is induced by adding 0.05 ml (20 ug/ml) ADP (adenosine diphosphate). Collagen-induced aggregation is evaluated by adding 0.1 ml collagen suspension to 0.45 ml PRP. Following the addition of the aggregating agent, the course of the reaction is monitored by an XY recorder. The extent of aggregation (max. aggregation) is obtained by determining the difference between the initial and final optical densities. Rates of aggregation are determined as the slopes of the ascending portion of the tracing. Percent of inhibition produced by compound administration is calculated as the inhibition of the change in aggregation between compound and vehicle treated adjuvant-injected rats normalized by the values obtained for vehicle treated noninjected control rats. The absence of a response to the addition of collagen indicates 100% blockade. The results in Table I below by way of illustration demonstrate that the compounds of this invention are useful in the inhibition of ADP induced platelet aggregation. Comparable data for Aspirin, the drug commonly used to inhibit platelet aggregation in mammals, is included in Table I. These results show that the compounds of this invention are efficacious at a lower dose than the reference drug.

TABLE I

Treatment	Dose mg/kg	Percent Inhibition of Extent of Aggregation		Percent Inhibition of Rate of Aggregation
		Aspirin	1-(3-Carboxyphenyl)-2-phenyl-4,5,6,7-tetrahydroindole	
	50	0	61	57
	75	35	59	0
	50	61	77	8
	50	59	77	77
	50	30	30	13

TABLE I-Continued

EFFECT ON ADP-INDUCED PLATELET AGGREGATION ON TENTH DAY IN ADJUVANT-INDUCED ARTHRITIC RATS

Treatment	Dose mg/kg	Percent Inhibition of Extent of Aggregation	Percent Inhibition of Rate of Aggregation	
hydroxyphenyl)-2-phenyl-4,5,6,7-tetrahydroindole				5
1-(3-Carboxy-4-hydroxyphenyl)-2-phenyl-4,5,6,7-tetrahydroindole	50	47	16	10
1-(3-Carboxy-4-hydroxyphenyl)-2-phenyl-1,4,5,6-tetrahydrocyclopenta[b]pyrrole	50	19	14	
3-(3-Carboxy-4-hydroxyphenyl)-4,5-dihydro-2-phenylbenz[e]indole	50	66	100	15
3-(3-Carboxy-4-hydroxyphenyl)-2-phenylbenz[e]indole	50	41	45	

The results in Table II below by way of illustration demonstrate that the compounds of this invention are useful in the inhibition of collagen-induced platelet aggregation. Comparable data for Aspirin is also included. The results again demonstrate that the compounds of this invention are efficacious at a lower dose than the reference drug.

TABLE II

EFFECT ON COLLAGEN INDUCED PLATELET AGGREGATION ON TENTH DAY IN ADJUVANT-INDUCED ARTHRITIC RATS

Treatment	Dose mg/kg	Observed Effect	
Aspirin	200	100% Blockade	
1-(3-Carboxy-4-hydroxyphenyl)-4,5-dihydro-2-phenylbenz[e]indole	50	No Blockade	
1-(3-Carboxy-4-hydroxyphenyl)-2-phenyl-4,5,6,7-tetrahydroindole	50	100% Blockade	
1-(3-Carboxy-4-hydroxyphenyl)-2-phenyl-1,4,5,6-tetrahydrocyclopenta[b]pyrrole	50	Partial Blockade	40
3-(3-Carboxy-4-hydroxyphenyl)-4,5-dihydro-2-phenylbenz[e]indole	50	Partial Blockade	
3-(3-Carboxy-4-hydroxyphenyl)-2-phenylbenz[e]indole	50	100% Blockade	45
3-(3-Carboxy-4-hydroxyphenyl)-2-phenylbenz[e]indole	50	100% Blockade	50

In vitro studies are performed using human platelets obtained by centrifuging blood samples obtained from the antecubital fossa of a normal human volunteer and processed in the same manner as the rat blood samples to obtain PRP and PPP. Platelet aggregation studies are performed as described above using 0.45 ml PRP (500,000 platelets/mm³) plus 0.05 ml test compound or Plain Tyrodes Buffer and 0.05 ml of either ADP, Collagen, or epinephrine (10⁻⁴M). Aqueous solutions of test compounds 3-(3-carboxy-4-hydroxyphenyl)-4,5-dihydro-2-phenylbenz[e]indole and Aspirin are prepared and all dilutions made with Plain Tyrodes Buffer. 0.45 ml PRP and 0.05 ml test compound are incubated 3 minutes at 37°C prior to the addition of the aggregating agent. The results in Table III below indicate that on a molar basis 3-(3-Carboxy-4-hydroxyphenyl)-4,5-dihydro-2-phenylbenz[e]indole is more effective than the reference drug (Aspirin) in in-

hibiting ADP, Collagen and epinephrine induced platelet aggregation.

TABLE III

INHIBITION OF ADP, COLLAGEN AND EPINEPHRINE-INDUCED AGGREGATION OF HUMAN PLATELETS IN VITRO

Compound	Final Molar Concentration	Aggregating Agent	Percent Inhibition of Maximum Aggregation
3-(3-Carboxy-4-hydroxyphenyl)-4,5-dihydro-2-phenylbenz[e]indole	6 × 10 ⁻⁷	ADP	42.9
	1.2 × 10 ⁻⁶	Collagen	81.8
	1.2 × 10 ⁻⁵	Epinephrine	41.2
Aspirin	1.25 × 10 ⁻⁶	ADP	45.2
	1.25 × 10 ⁻⁶	Collagen	25.6
	2.5 × 10 ⁻⁵	Epinephrine	51.5

Clinical studies in human volunteers indicate that single oral doses of 100 or 250 mg of 3-(3-carboxy-4-hydroxyphenyl)-4,5-dihydro-2-phenylbenz[e]indole effectively suppress ADP induced platelet aggregation and block collagen induced platelet aggregation.

For preventing thrombosis and preventing platelet aggregation, the compounds are preferably administered orally in a suitable formulation containing effective dosages, which are in the range of about 0.5 to about 50 mg/kg of body weight per day. To inhibit platelet aggregation in plasma, the compounds are added to the plasma in effective amounts sufficient to form between about 1 × 10⁻⁷ to 1 × 10⁻⁴ molar concentrations.

We claim:

1. A method of preventing thrombosis and inhibiting platelet aggregation in mammals which comprises administering to a mammal an effective amount of a compound of the formula:

wherein

X is hydrogen or hydroxy; Y is hydrogen, hydroxy, halogen, alkyl of one to four carbon atoms, alkoxy of one to four carbon atoms, or trifluoromethyl; and Z is alkylene of three to five carbon atoms, alkylene of three to five carbon atoms substituted by alkyl or alkoxy of one to four carbon atoms, divinylene, divinylene substituted by alkyl of one to four carbon atoms,

5

5

2. A method of preventing thrombosis and inhibiting 10 platelet aggregation in mammals which comprises administering to a mammal an effective amount of a compound of the formula:

15

20

or

25

5. A method of inhibiting platelet aggregation in blood plasma which comprises adding to the plasma an effective amount of a compound of the formula:

wherein

X is hydrogen or hydroxy and Z is alkylene of three to five carbon atoms,

30

35

3. The method defined in claim 2, wherein the effective compound is 3-(3-carboxy-4-hydroxyphenyl)-4,5-dihydro-2-phenylbenz[e]indole.

4. A method of inhibiting platelet aggregation in 40 blood plasma which comprises adding to the plasma an effective amount of a compound of the formula:

wherein

45 X is hydrogen or hydroxy and Z is alkylene of three to five carbon atoms,

50

6. The method defined in claim 5, wherein the effective compound is 3-(3-carboxy-4-hydroxyphenyl)-4,5-dihydro-2-phenylbenz[e]indole.
